(57) **CLAIM**

The ornamental design for a building scaffolding brace assembly as shown and described.

DESCRIPTION

FIG. 1 is a perspective view of the building scaffolding brace assembly;

FIG. 2 is a front view of the building scaffolding brace assembly of FIG. 1;

FIG. 3 is a rear view of the building scaffolding brace assembly of FIG. 1;

FIG. 4 is a right side view of the building scaffolding brace assembly of FIG. 1;

FIG. 5 is a left side view of the building scaffolding brace assembly of FIG. 1;

FIG. 6 is a top view of the building scaffolding brace assembly of FIG. 1; and,

FIG. 7 is a bottom view of the building scaffolding brace assembly of FIG. 1.

The broken lines in the drawings are included for the purpose of illustrating portions of the building scaffolding brace assembly and form no part of the claimed design.
